UNITED STATES PATENT OFFICE.

GUTIE H. TUTTLE, OF MONTGOMERY, ALABAMA, ASSIGNOR OF NINE-TENTHS
TO WILLIAM W. BUFORD, OF DONALDSONVILLE, LOUISIANA.

ROTARY ENGINE.

SPECIFICATION forming part of Letters Patent No. 600,753, dated March 15, 1898.

Application filed July 8, 1897. Serial No. 643,802. (No model.)

To all whom it may concern:

Be it known that I, GUTIE H. TUTTLE, of 5
Montgomery, in the county of Montgomery
and State of Alabama, have invented a new
and Improved Rotary Engine, of which the
following is a full, clear, and exact descrip-
tion.

My invention relates to an improvement in
rotary engines, and comprises a casing hav- 10
ing a cylindrical chamber or cavity therein
and a rotary disk of smaller diameter than the
cavity, said disk having a projecting abut-
ment with an incline upon one side and act-
ing as a piston, and the casing having a slot 15
receiving a sliding abutment, which acts also
as a valve to cut off and admit the steam.

The invention also consists of certain de-
tails of construction, which will be hereinafter
described and claimed.

Reference is to be had to the accompanying
drawings, forming a part of this specification,
in which similar characters of reference indi-
cate corresponding parts in all the views.

Figure 1 is a sectional elevation on the line
1 1 in Fig. 2. Fig. 2 is a section on the line
2 2 in Fig. 1. Fig. 3 is a top plan view of the
engine complete. Fig. 4 is a side elevation
of the plate forming one head of the cylinder.
Fig. 5 is a section taken upon the line 5 5 of
Fig. 4. Fig. 6 is an elevation of the rotary
disk with one of the projecting abutments.
Fig. 7 is a plan view of the spring which is
attached to the sliding abutment; and Fig. 8
is an elevation of the lower part of the slid-
ing abutment, the last two figures showing
the method of connecting these two parts to-
gether.

The engine comprises two cylinders formed
in one casing, which consists of the central
40 web A, having a rim A' projecting beyond the
web at each side, forming a cylindrical cas-
ing the open end of which is inclosed by the
cylinder-heads B. A shaft D is mounted in
the center of this casing and carries two
45 wheels or disks C, each occupying one of the
chambers formed in the casing. These wheels
C are circular in outline and preferably are
made with the outer rim projecting, as at C',
so as to fit the underside of a groove b', formed
50 in the heads B, and a similar groove formed
in the central web A of the casing.

To opposite sides of the wheel or disk C are
attached two abutments E. These abutments
are provided with a packing-strip E² to make
a steam-tight contact with the outer periph- 55
ery of the cylindrical chamber. Upon one
side they are provided with a cam or incline
E', adapted to engage the sliding abutment
to raise it as the abutment E passes the same.
Preferably the abutment E and cam or incline 60
E' are made separate from the disk and at-
tached thereto by bolts.

The annular chamber C', surrounding the
disk C, is of the same size at all points, ex-
cept that on one side, and extending from the 65
sliding abutment in a direction therefrom
opposite the direction of rotation of the disk
is a recess a upon its outer periphery to re-
ceive a flat spring J. This spring is secured
at one end to the sliding abutment F by means 70
of dovetail tongues J', fitting into similar
grooves f in the lower end of the abutment F.
At its opposite end it is secured to the outer
surface of the cylinder-chamber by means of
suitable screws. This spring J is a spring- 75
plate and is adapted to yield under the action
of the cam or incline E', so as to force the
spring into the recess a in the cylinder. As
the spring J rises the abutment F is raised,
so that the piston-head formed by the abut- 80
ment E may pass under the same. The up-
per end of the plate F, forming the movable
abutment, lies just below the steam-port G
when the abutment is resting upon the sur-
face of the disk C. As the abutment rises 85
under the influence of the incline E' it closes
the steam-port, thus cutting off the supply
of steam. As soon as the piston-head E has
passed the abutment F the latter will drop
down under the influence of the spring-plate 90
J. This admits steam through the port G
and behind the piston-head E.

The exhaust-port is located at I, being at
an angle of about ninety degrees from the
steam-port G. As before stated, two piston- 95
heads or abutments E are attached to each
of the disks C, being attached at an angle of
about ninety degrees upon opposite disks—
that is, the abutment upon the disk upon one
side alternates with the abutment upon the 100
other disk, thus bringing one of the abut-
ments or piston-heads into use at all times.

Through that portion of the circumference of the cylinder which is filled with live steam a strip *b* is placed upon both the head *B* and the central flange *A*. This strip is placed so as to be in close contact with the inner surface of the outer edge of the wheel or disk *C*, as is clearly shown in Fig. 2. This construction makes a tighter joint than would otherwise be obtained. The spring-plate *J* is to be so proportioned and constructed that the pressure of the abutment *F* upon the disk shall be very slight, thus avoiding a large amount of friction ordinarily due to the use of such an abutment and also makes the same easy to raise under the influence of the incline *E'*.

The steam-pipe *H*, delivering steam to the engine, is forked into two branches *h*, so as to deliver the steam to each side of the engine.

Having thus described my invention, I claim as new and desire to secure by Letters Patent—

A rotary engine comprising a cylinder having steam supply and exhaust ports and a radially-extending slot adapted to receive a movable abutment and extending across the supply-port, an abutment in said slot adapted to open said port when in its inner position, a curved flat spring adapted to extend about a portion of the upper periphery of the cylinder-chamber and connected at one end to the cylinder and at the other end having fingers dovetailed into the inner end of the abutment, thereby forming a yielding or sliding connection with said abutment, the cylinder being provided with a peripheral recess adapted to receive said spring, and a rotating piston-disk having an abutment or head thereon having an incline adapted to raise a movable abutment.
